UNITED STATES PATENT OFFICE.

CARL E. J. ANDERSON, OF YOUNGSTOWN, OHIO.

APPARATUS FOR TREATING PLACER.

1,088,760.

Specification of Letters Patent.

Patented Mar. 3, 1914.

Application filed February 9, 1912. Serial No. 676,515.

To all whom it may concern:

Be it known that I, CARL E. J. ANDERSON, a citizen of the United States, and a resident of Youngstown, county of Mahoning, and State of Ohio, have invented a new and useful Improvement in Apparatus for Treating Placer, of which the following is a specification, the principle of the invention being herein explained and the best mode in which I have contemplated applying that principle, so as to distinguish it from other inventions.

My invention relates to a process for separating out precious metals from placer without the use of water or other liquid. It is of great importance to be able to accomplish the above named result without the use of a liquid, since in many places where placer is found there is no water to be had.

To the accomplishment of these and related ends, said invention then consists of the means hereinafter fully described and particularly pointed out in the claim.

The annexed drawing and the following description set forth in detail certain mechanism adapted to carry out the invention, such disclosed means constituting, however, but one of various mechanical forms which the apparatus for the invention may take.

In said annexed drawing: Figure 1 is a side elevation of my apparatus partially in section; Fig. 2 is a section of the line 2—2 in Fig. 1; Fig. 3 is a section of the line 3—3 in Fig. 1; and Fig. 4 is a section through the apparatus, but taken on the line 4—4 in Fig. 2.

Various types of apparatus may of course be used in carrying out the process to be hereinafter described but a simple and effective mechanism for such purpose will now be described.

In Fig. 1 the placer is fed into feed box 1 which is controlled by means of a door or gate 2 sliding in supports 3. The placer will flow through this gate and will be sucked up by air which enters through two air doors 4, one on either side of the feed box. The placer and air will enter a cylindrical casing 5 which is controlled at the inlet end by a gate 6 controlling an opening in a partition 7. The cylindrical casing 5 is provided with a shallow trough 8 at the bottom which is adapted to receive a tray 9 bearing riffles 10 and containing mercury. This tray may be removed through a door 11 at the end of the trough. A second door 12 is provided in the side of the casing for

the purpose of permitting inspection and cleaning of the casing. At the exhaust end the casing is narrow and is attached to a conduit 13 which may be carried to any convenient depository as desired. Journaled in the ends of the casing is a shaft 14 having a pulley 15 fixedly mounted on its exterior end and adapted to be driven by any suitable means of power. Bearings 16 for the shaft are provided at intervals along the casing and are of the form shown in Fig. 2. Upon the shaft are mounted fans 17 which are adapted to create a powerful draft through the casing in the direction of the arrows. It will be obvious that the air will travel not only through the casing but spirally around the central shaft.

The operation of the machine will now be described. The placer containing its precious metal deposits will be sucked in at the feed box by means of the draft and will be forced through the casing with a spiral movement. The draft will be maintained at a speed which is sufficient to carry along the waste material in the placer, but not the heavier precious metals. This action will be readily understood. The gold is about eight times as heavy as the waste and the silver about four times. It is a simple matter to so graduate the speed maintained that the waste material will be carried from the casing while the heavier metals are allowed to deposit in the trough. In addition to the action of gravity on the heavier metals there is a centrifugal action due to the spiral course taken by the air blast caused by the rotary action of the fans. In this way the placer is thrown radially outward toward the sides of the casing, the heavier particles striking the sides with the greater force, or rather reaching the sides, since the speed is so great that only the heaviest material will ever reach the sides of the casing. When the metal strikes the sides, however, it will move spirally around until it comes to the trough at the bottom of the casing. It will here deposit and will amalgamate with the mercury which is contained in the riffle pans.

From the foregoing description of the operation it will be seen that no liquid is required to operate the present machine. This is considered a considerable advance in placer working, since many deposits which have hitherto been inaccessible for lack of water are now opened to working on either small or large scales. By the dou-

ble action of gravity and centrifugal force a high percentage of the gold carried by the placer is obtained, even though no water is used in the process.

- 5 It will of course be possible to use my apparatus as an ore concentrator in which case quartz ore will be crushed sufficiently to free the precious metals and will then be drawn in the apparatus as is the placer already described. The action of the apparatus as a concentrator is equally as efficient as the operation of the placer machine and I do not limit myself to either one of such uses.
- 10 15 Other modes of applying the principle of my invention may be employed instead of the one explained, change being made as regards the mechanism herein disclosed, provided the means stated by the following claim or the equivalent of such stated means be employed.

Copies of this patent may be obtained for five cents each, by addressing the "Commissioner of Patents, Washington, D. C."

I therefore particularly point out and distinctly claim as my invention:—

In apparatus of the class described, the combination of a substantially horizontally disposed casing having an opening at one end; a trough at the bottom of said casing adapted to receive riffle boards; a valve adapted to control such opening in said casing; a shaft rotatably mounted in said casing; fans attached to said shaft and adapted when rotated thereby, to produce a draft in said casing away from such opening of sufficient force to draw placer through such opening and through said casing.

Signed by me this 4th day of January 1912.

CARL E. J. ANDERSON.
